UNITED STATES PATENT OFFICE.

MILLARD F. BROWN, OF EAST RINGGOLD, OHIO.

GRAVE-VAULT.

SPECIFICATION forming part of Letters Patent No. 309,025, dated December 9, 1884.

Application filed May 3, 1884. (No model.)

To all whom it may concern:

Be it known that I, MILLARD F. BROWN, a citizen of the United States, and a resident of East Ringgold, in the county of Pickaway and State of Ohio, have invented certain new and useful Improvements in Portable and Adjustable Grave-Vaults; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of my improved portable or removable grave-vault. Fig. 2 is a vertical section of the same. Fig. 3 is a cross-section. Fig. 4 is a top view, and Figs. 5, 6, 7, and 8 are perspective detail views of the several parts of the vault.

Similar letters of reference indicate corresponding parts in all the figures.

My invention has relation to removable grave-vaults; and it consists in the improved construction and combination of parts of the same, as hereinafter more fully described and claimed.

In the accompanying drawings, the letter A indicates a rectangular frame of metal, of a suitable size to be placed in the grave and to have the coffin lowered through it, and is provided at its corners with slots B, and with notches C at equal distances in its outer edges. The upper reduced ends or tenons, D, of the removable side slats, E, fit into these notches, and have inwardly-bent strips F at their upper ends, which strips have perforations G at their inner ends, registering with perforations H in the rectangular frame. The lower ends of these slats, which are of any suitable metal, have a recess, I, and a transverse perforation, J, forming one-half of a pintle-hinge, and the reduced outer ends, K, of the outer bottom blocks, L, are hinged in the recesses upon pins M, and the inner reduced ends of these blocks are hinged in a similar manner to the outer ends of the inner bottom blocks, N. A plate, O, having a perforation, P, is hinged upon the middle of the inner side of each slat, the said perforation in the plate registering with the perforation in the rectangular frame, and with a perforation, Q, in the outer bottom block, and with a perforation, R, in a wooden bottom

frame, S, all the perforations serving to receive a long rod or bolt, T, having a head upon its upper end and screwing into the perforations in the outer bottom blocks, its lower end being threaded and the said perforation being threaded. The corner slats, U, are constructed in the same manner as the side slats, with the exception of their being wider than the side slates, so as to enable them to extend out at the corner to form a square corner, and their upper ends are provided, besides the reduced ends or tenons, with tenons V, fitting in the slots in the corners of the rectangular frame, and extending above them, having perforations or recesses adapted to receive locking-bolts. The entire upper open side of the vault is covered with a removable flanged cover, W, provided with suitable handles, X, and having suitable locks, Y, or other fastening means, by means of which the cover may be securely attached to the remainder of the vault.

When it is desired to use the vault outside of a grave, the bottom blocks are provided at one side with projecting lugs Z upon their upper sides, and with hinged bails A' at the other side, which bails may be hooked over the lugs upon the opposite bottom blocks, 80 serving to hold the said blocks together, the wooden bottom being dispensed with.

It will be seen that the vault may be built in the grave, resting upon the wooden base-plate, receive the coffin, and be closed, the 85 cover locked upon the ends or tenons of the corner-posts preventing the entire vault from being tampered with, and after the body has been sufficiently long time in the grave to preclude any possibility of its being taken 90 away, or for any other reason whatever, the cover may be removed, the bolts taken out, when the rectangular frame may be raised and the slats be drawn from under the bottom of the coffin, the hinged bottom pieces slipping under the bottom of the coffin, until at last the wooden base-plate is all that remains, when the grave may be filled and the vault used for another grave.

Having thus described my invention, I claim 100 and desire to secure by Letters Patent of the United States—

1. The combination of the rectangular frame, the slats having flexible bottom bloc-

hinged to their lower ends, means for securing the slats to the frame, the flanged cover, and means for securing the cover to the upper ends of the end or corner slats, as and for the purpose shown and set forth.

2. The combination, in a grave-vault composed of metallic slats, of the side slats upon one side, having flexible bottom blocks hinged to their lower ends, provided with upwardly-projecting lugs, and the side slats of the other side, having flexible bottom blocks provided with hinged bails adapted to engage the projections upon the blocks upon the other side, as and for the purpose shown and set forth.

15 3. The combination of the rectangular frame having notches in its edges and perforations corresponding with the notches, the side slats having reduced upper ends fitting in the notches in the frame, and having inwardly-bent perforated strips upon their reduced upper ends, the flexible bottom blocks having threaded perforations, and the bolts or rods having their lower ends screw-threaded, as and for the purpose shown and set forth.

25 4. The combination of the rectangular frame having notches in its outer edges and perforations corresponding with the notches, the slats having their upper ends reduced, fitting in the notches in the frame, and provided with inwardly-bent perforated strips, the perforated plates hinged upon the middle of the inner sides of the slats, the outer bottom blocks hinged to the lower ends of the slats and hav-

ing vertical threaded perforations, the inner bottom blocks hinged to the inner ends of the outer blocks, and the bolts or rods threaded at their lower ends, as and for the purpose shown and set forth.

5. The combination of the rectangular frame having notches in its outer edges, perforations corresponding to the notches and slots in its corners, the slats having perforated strips at their reduced ends, hinged plates upon the middle of their inner sides, and perforated flexible bottom blocks, the corner slats having hinged perforated plates, perforated hinged flexible bottom blocks, reduced upper ends having inwardly-bent perforated strips, and the longer tenons having perforations or recesses for the reception of locking-bolts, the bolts or rods having threaded lower ends, the wooden detachable bottom having perforations corresponding to the perforations in the bottom blocks, and the flanged cover having means for engaging the recessed or perforated ends of the corner slats, as and for the purpose shown and set forth.

In testimony that I claim the foregoing as my own I have hereunto affixed my signature in presence of two witnesses.

MILLARD F. ^{his} X BROWN.
